METHOD AND APPARATUS FOR PREVENTING SURGING IN FANS, BLOWERS, AND TURBO-COMPRESSORS

Hidetoshi Kusama and Shigeru Tsuji, Tokyo-to, Japan, assignors to Ebara Manufacturing Co., Ltd., Tokyo, Japan, a corporation of Japan

Filed Mar. 19, 1956, Ser. No. 572,551

4 Claims. (Cl. 230—19)

The present invention relates to a method and apparatus for preventing the effect of surging in the compressed fluid delivery line in conjunction with high-speed and high-pressure blowers or turbocompressors.

The fluid flow is steady, or practically so, in many installations of a blower and connected piping. Cases have been reported, however, in which marked periodic fluctuation has been superposed upon the main steady flow. This fluctuation has been called "surging." In some cases of centrifugal compressors, the surging is a very important factor. Surging is more pronounced with centrifugal compressors than with fans; it may cause the compressor to become out of order, and it may limit the useful range of operation of the machine.

Surging occurs when operation is in a region in which the blower characteristic shows an increase in pressure with an increase in volume rate of flow. Surging does not occur when the blower characteristic shows a decrease in pressure with an increase in capacity. Surging tends to occur when the volume of the connected piping system is relatively large. A relatively large volume can be realized with relatively long pipes and large diameters.

Surging cannot be explained adequately in very simple terms because the action, like many vibratory actions, is quite complicated. Many different factors are involved, each of which is essential to the complete phenomenon.

It has heretofore been proposed to provide a by-pass to waste on the discharge side of the blower, thereby to operate the blower at a capacity above that for the peak pressure, thus eliminate surging.

Furthermore, it has heretofore been proposed to provide in an appropriate part of the delivery channel of the blower an opening controlled by a valve and to open such valve when the power of the blower falls.

Generally speaking, the heretofore proposed methods for preventing the surging of blowers are enumerated as follows: (1) machine designers have endeavored to obtain the falling characteristic of the blower, even though the efficiency is considerably reduced; (2) blowers are operated in the safety region by discharging excess fluid by a by-pass to waste; (3) the operating capacity of the blower is controlled by a valve installed in the inlet channel; (4) the operation at reduced capacity is made possible by reducing the rotating speed.

The machine designer has remodelled the shape of an impeller, or a guide vane of a blower so that the blower can be operated in a stable region of the blower characteristic in order to obviate the surging. The efficiency of the blower, however, cannot help being reduced considerably by such remodelling of machine elements. Besides, the means such as, suction vane control and a variable speed motor, have been applied to disadvantage in respect of construction.

We have discovered that the above-mentioned surging can be eliminated effectively by providing a surge-preventing valve on the discharge channel of the blower.

It is an object of our invention to provide a surge preventing device which is very simple in principle, but is subject to installation in any type of the blower.

Another object of the invention is to provide a surge preventing device generally useful and effective in a blower or compressor.

Another object of the invention is to provide a surge preventing device which minimizes the unfavorable effects of heavy surges and eliminates knocking and pounding of both large and small surges.

Another object of the invention is to provide a surge preventing device which eliminates the disagreeable effects of fluctuation in pressure and volume rate of flow caused by the surging and assures the smooth and continuous operation of the machine.

Another object of the invention is to provide an automatic surge preventing device which can proceed through a complete cycle of operation once its operation has been initiated.

Another object of the invention is to provide a surge preventing device by which a considerable amount of power cost can be saved.

With the above and other objects in view that will hereinafter appear, the nature of the invention will be more fully understood by following the detailed description, the appended claims, and the views illustrated in the accompanying drawings, in which:

Fig. 1 shows the characteristic curve of a blower, surging region, surging stable region, and resistance curves showing maximum and minimum limits of surge prevention, respectively.

Fig. 2 is a plan of the hydraulic control of our surge preventing apparatus.

Fig. 3 is a plan of the modified hydraulic control of the surge preventing apparatus of the invention.

Fig. 4 is a plan of the electronic hydraulic control of the surge preventing apparatus of the invention.

In the figures like reference characters indicate like parts. Referring more particularly to the drawings, Fig. 1 shows the characteristic curve of a blower and the connected piping system. The abscissa is the capacity or volume rate of flow. The ordinate is the pressure developed by the blower and the valves.

As the capacity increases, pressure first increases, reaches a peak, and then decreases. For the piping system the pressure drop increases as the velocity of flow increases. In accordance with our invention, we provide a surge-preventing valve on the discharge channel of the blower. We call a valve heretofore employed in general

a capacity-control valve. In the following disclosure the resistance value of the capacity-control valve in question includes various resistance values, such as, pipe friction and load in general. Assume that a given volume of flow Q_B is obtained in the discharge channel of the blower with an appropriate opening of the capacity-control valve. The volume rate of flow Q_B is determined linearly by the resistance of the capacity-control valve. If the given volume rate of flow Q_B is found in the surging limit, then surging takes place. At the constant

volume rate of flow Q_B , we throttle the surge-preventing valve slowly, then we assume the resistance loss value of the first valve to be the value shown by hB_1 when surging ceases. The term, "load" means the space or chamber wherein the compressed fluid energy is consumed, and "resistance loss value" means the energy loss value. Again we throttle the surge-preventing valve and open the second valve with the same volume rate of flow Q_B , accordingly surging occurs again, then we assume the resistance loss value of the surge-preventing valve to be hB_0 . In accordance with the different volume rate of flow, we plot the curves OB_1L_1 and OB_2L_2 . Surging occurs when the resistance loss value of the

surge-preventing valve is found in the lower region defined by the curve OB_1L_1 , and the abscissa, and the upper region defined by the curve OB_2L_2 , the characteristic curve, and the ordinate. Consequently, the resistance loss value of the surge-preventing valve is preferably to be found in the surging stable region, except the hatched regions shown by $OAB_4L_2B_2$ and $OB_1L_1B_0$, in order to prevent surging. The resistance loss value of the capacity-control valve depends upon that of the surge-preventing valve. For example, if the value of the surge-preventing valve is shown by B_0B_3 at the volume rate of flow Q_B , the value of the capacity-control valve is shown by B_3B_4 .

As described above, the surge preventing apparatus of our invention is a very simple one consisting of the surge-preventing valve provided on the discharge channel of the blower. The mathematical analysis of our invention will be found in our article, Transactions of the Japan Society of Mechanical Engineers, vol. 22, No. 117 (1956). Though very simple in principle, however, the preferred forms of the control mechanism of the surge-preventing valve are enumerated as below. It is to be understood that the preferred embodiments of the invention herein described are for illustrative purposes only, but not limited thereto. As described hereinbefore, the term "load" means the space or chamber in which the compressed fluid energy is consumed. More particularly, for example, the load may be the blast furnace into which the pressure hot air is delivered through the tuyere, or the chemical reactor into which the compressed fluid of constant pressure is continuously delivered.

The three methods of control are as follows:

- (1) Hydraulic control.
- (2) Modified hydraulic control.
- (3) Electronic hydraulic control.

Now we explain the necessity of an air chamber 65 as shown in the drawings. The volume between two valves is important in order to prevent surging in accordance with the operation of two valves. If the volume is below a predetermined volume for a given blower and its connected piping system, surging cannot be obviated by our invention. For instance, our experiment has shown that the volume between two valves must be at least 80 litres for a blower with capacity 1,500 mm. of the height of water column. Therefore an air chamber 65 is preferably provided on the delivery channel 7.

Referring to Fig. 2, in event of our desire to control the volume rate of flow, we change the opening of the capacity-control valve plate by turning the hand wheel 17, then the varied volume rate of flow will result in the change of suction pressure at the inlet nozzle 5, thereby operating a servo-mechanism, i.e., the liquid enclosed in the ring balance 51 will move to the direction of an arrow when the rate of flow increases. Then the ring balance 51 will be shifted clockwise in order to maintain equilibrium. The cam 27 is secured to the shaft 53 of the ring balance 51 so that the cam 27 will be shifted clockwise, therefore the piston 28 of the pilot valve or servo-valve 66 will slide downward so that the port 30 is in open communication with the port 37, and the oil delivered from the oil accumulator 38 is supplied through the conduit 40 into the lower space of the servomotor 67, thereby the piston 33 of the servomotor 67 will be lifted so that the surge-preventing valve plate 3 will be raised because the stem 9 of the valve plate 3 is secured to the piston 33. On the other hand, the lever 68 of the return or follow-up mechanism is held on the fulcrum 34, and one end of the lever 68 is secured to the piston 33 of the servomotor 67, and the other end to the cylinder of the pilot valve 66, so that with the lift of the servomotor piston 33, the cylinder of the pilot valve 66 will be lowered, thereby the ports 30 and 37

are in closed position, and the pilot valve 66 and the piston 28 resume their initial positions.

Referring to Fig. 3, the increased volume rate of flow by opening the capacity-control valve plate 4 actuated by the valve hand wheel 17 will result in the pressure difference between the two spaces of the actuator 42, thereby also operating a servo-mechanism, i.e., cause the diaphragm 43 to move in the direction of the arrow. The stem 44 is secured to the diaphragm 43, so that the stem 44 will move in the direction of the arrow. The swinging pipe element 69 of the distributing valve 50 is held on the fulcrum 34, so that the movement of the stem 44 will cause the swinging pipe element 69 to move to the same direction as the arrow. The port 48 is in open communication with the port 32, so the oil 39 delivered from the accumulator 38 will enter the lower space of the servomotor 67 through the port 47, thereby permit the piston 33 to lift upward, then the surge-preventing valve 3 is in open position. On the other hand, the oil in the lower space of the servomotor 45 will enter the upper space of the servo-valve cylinder 46 of the return or follow-up mechanism through the port 70, and drive the piston 71 downward. In consequence, the swinging pipe element 69 becomes stable, and resumes its initial position.

Referring to Fig. 4, this control mechanism can be applied to the machine in which the inlet nozzle 5 is situated at the relatively long distance from the surge-preventing valve. The increased volume rate of flow at the opening of the capacity-control valve plate 4 actuated by the hand wheel 17 will result in the depression of the air pressure in the lower space of the actuator 42, so that the diaphragm 43 is lowered operating a servo-mechanism. The rotor 72 of the self-synchronized motor 54 is linked to the stem 44 secured to the diaphragm 43, therefore the downward movement of the diaphragm 43 will rotate the rotor 72 of the self-synchronized motor 54 by means of the stem 44. Consequently, it will influence the intensity of the magnetic field of the self-synchronized motor 54, the intensity will be transmitted to the self-synchronized motor 56 by means of the circuit 55, then the intensity of the magnetic field will vary, the amount of varied intensity will be transmitted to the secondary winding of a transformer 57. In other words, there is provided a diaphragm motor responsive to the inlet pressure of said blower and an electrical motor responsive to the movement of said diaphragm motor. The varied voltage herein obtained will be amplified by the electron tubes 58 and 59, then transmitted to the field coil of a motor 60, which will be energized to cause the rotor 73 of the motor to perform the rotary motion. The rotation of the rotor 73 will shift the sliding-piece 62, because the rotor 73 is connected to the sliding-piece 62 of the rheostat 61. An angle displacement of the sliding-piece 62 corresponds linearly to the value of the pressure derived from the inlet nozzle. The resistance value of the rheostat 61 is chosen as it is proportional to the square of the electric current. The current through the circuit 74 is amplified, and altered by the displaced angle of the sliding-piece. As the coil 63 is included in the circuit 74, the intensity of the magnetic field of the coil 63 varies as the current varies, therefore it causes the iron core 64 of the coil to go downward, so that the rod connected thereto will be lowered. As the piston 28 of the pilot valve 66 is connected to the rod, the oil delivered from the accumulator 38 is supplied through the conduit 40 into the lower space of the servomotor 67, because the ports 30 and 37 are now in open communication, thereby the piston 33 of the servomotor 67 will be lifted so that the surge-preventing valve plate 3 will be raised to the position where the resistance value of the valve reaches the value necessary for preventing surging because the stem 9 of the surge-preventing valve plate 3 is secured to the piston 33. On the other hand, the lever 68 of the return

mechanism is held on the fulcrum 34, and one end 36 of the return mechanism is secured to the piston 33 of the servomotor 67, and the other end 35 to the cylinder of the pilot valve 66, so that with the lift of the servomotor piston 33 the cylinder of the pilot valve 66 will be lowered, the pilot valve 66 and the piston 28 resume their initial positions.

From the foregoing description, taken in connection with the accompanying drawings, it is thought that the novel details of construction, the manner of use, and the advantages of the invention, will be apparent to those skilled in the art to which it relates.

It is, of course, to be understood that the details of structure and arrangement of parts may be variously changed and modified without departing from the spirit and scope of our invention as set forth in the appended claims.

Having thus described the invention, what we claim as new and desire to secure by Letters Patent, are:

1. In a blower system for controlling the supply of compressed fluid to a load, a blower for supplying said fluid under pressure to said load, an inlet channel communicating with the inlet of said blower, a discharge channel communicating with the discharge of said blower and with said load, a manually operated capacity-control valve positioned in said discharge channel adjacent said load on the inlet side thereof, a surge preventing valve positioned in said discharge channel adjacent said blower and servo-mechanism for controlling the movement of said surge preventing valve, said servo-mechanism including an inlet conduit communicating with said blower inlet channel, control means communicating with said inlet conduit and responsive to the inlet pressure of said blower, said control means being operatively connected to a servo-valve for controlling the operation thereof, a servo-motor communicating with said servo-valve and connected to said surge valve, said servo-motor being responsive to movement of said servo-valve to control the movement of said surge valve, and a follow-up mechanism responsive to movement of said servo-motor and operatively connected to said servo-valve for restoring

said servo-valve to the original position thereof, thereby positioning said surge preventing valve within predetermined limits.

2. In a blower system as set forth in claim 1, said servo-valve including a pivotally mounted inlet pipe that introduces control fluid therein, means connected to said control means and said inlet pipe and responsive to the inlet pressure of said blower for pivotally moving said inlet pipe, and control pipes communicating with opposite sides of the servo-motor piston, said inlet pipe pivoting into communication with either of said control pipes in response to operation of said pivoting means.

3. In a blower system as set forth in claim 1, said control means including a fluid responsive ring balance, a cam connected to said ring balance and to said servo-valve, said cam being responsive to movement of said ring balance to control the movement of said servo-valve.

4. In a blower system as set forth in claim 1, said control means including a diaphragm motor responsive to the inlet pressure of said blower, an electrical motor responsive to movement of said diaphragm motor and a magnetic coil having a core operatively connected to said control valve, said magnetic coil being responsive to rotation of said motor to control the movement of said coil and said control valve.
